(57) **CLAIM**

The ornamental design for a curling iron attachment, as shown and described.

DESCRIPTION

FIG. 1 is a front elevation view of a curling iron attachment, showing our new design;

FIG. 2 is a rear elevation view of FIG. 1;

FIG. 3 is a left side elevation view of FIG. 1;

FIG. 4 is a right side elevation view of FIG. 1;

FIG. 5 is a top plan view of FIG. 1;

FIG. 6 is a bottom plan view of FIG. 1; and,

FIG. 7 is a perspective view of FIG. 1, showing the curling iron attachment connected to an associated handle.

The broken lines in the drawings depict portions of the curling iron attachment that form no part of the claimed design. The broken lines showing the associated handle in FIG. 7 depict environmental subject matter that form no part of the claimed design.

1 Claim, 4 Drawing Sheets
